UNITED STATES PATENT OFFICE

109,749

DESIGN FOR AN ARM REST FOR A GLIDER OR SIMILAR ARTICLE

Ralph Weisman, Detroit, Mich.

Application March 5, 1938, Serial No. 75,627

Term of patent 7 years

To all whom it may concern:

Be it known that I, Ralph Weisman, a citizen of the United States, residing at Detroit, in the county of Wayne and State of Michigan, have invented a new, original, and ornamental Design for an Arm Rest for a Glider or Similar Article, of which the following is a specification, reference being had to the accompanying drawing, forming part thereof.

The figure is a perspective view of the arm rest showing my design.

I claim:

The ornamental design for an arm rest for a glider or similar article, as shown.

RALPH WEISMAN.
